(57) CLAIM

I claim the ornamental design for an infant hairpiece, as shown and described.

DESCRIPTION

FIG. 1 is a front view of an infant hairpiece shown being worn;

FIG. 2 is a front and top perspective view of the infant hair-
piece;

FIG. 3 is a front elevation view of the infant hairpiece;

FIG. 4 is a back elevation view of the infant hairpiece;

FIG. 5 is a bottom view of the infant hairpiece;

FIG. 6 is a top view of the infant hairpiece;

FIG. 7 is a left side view of the infant hairpiece; and,

FIG. 8 is a right side view of the infant hairpiece.

The broken lines shown in FIG. 1 are provided for environmental purposes only and form no part of the claimed design.
